UNITED STATES PATENT OFFICE.

THOMAS F. THOMPSON, OF MONESSEN, AND ALVA PORTER BALDWIN,
OF BELLE VERNON, PENNSYLVANIA.

CURTAIN-POLE.

No. 833,564.

Specification of Letters Patent.

Patented Oct. 16, 1906.

Application filed May 23, 1906, Serial No. 318,401.

To all whom it may concern:

Be it known that we, THOMAS F. THOMPSON, residing at Monessen, in the county of Westmoreland, and ALVA PORTER BALDWIN, 5 residing at Belle Vernon, in the county of Fayette, State of Pennsylvania, citizens of the United States of America, have invented certain new and useful Improvements in Curtain-Poles, of which the following is a specification, reference being had therein to the accompanying drawings.

This invention relates to certain new and useful improvements in curtain-poles; and the invention has for its object to provide a 15 simple and inexpensive pole for curtains that can be swung outwardly from a window, permitting of easy access being had to the window when the same is to be cleansed or renovated.

20 Another object of this invention is to provide a two-part pivoted pole and novel means for temporarily retaining the parts of the pole in longitudinal alinement with one another.

25 With these and other objects in view, which will more readily appear as the invention is better understood, the same consists in the novel construction, combination, and arrangement of parts to be hereinafter described and claimed.

Reference now being had to the drawings forming part of this specification, like numerals of reference designate corresponding parts throughout the several views, in which—

35 Figure 1 is a front elevation of a window-frame equipped with our improved curtain-pole. Fig. 2 is a cross-sectional view of the window-frame, illustrating a curtain-pole in plan. Fig. 3 is a front elevation of a curtain-pole, illustrating a modified form of construction. Fig. 4 is a plan of the same. Fig. 5 is 40 an end view of the pole. Fig. 6 is a side elevation of a modified form of bracket. Fig. 7 is a longitudinal sectional view of a coupling member used in connection with our improved pole, and Fig. 8 is a side elevation of the same.

To put our invention into practice, we provide a window-frame 1 with side brackets 2, 50 carrying upwardly-extending pins 3, upon which T-shaped connections 4 are pivotally mounted. In the one end of each connection is mounted a curtain-pole 5, while secured in the other end of said connection is a

suitable ornamentation 6. The curtain- 55 poles 5 are adapted to support curtains 6^a, and since the poles are pivotally mounted relative to the window-frame the curtains can be easily swung outwardly from said frame.

A particular feature of our invention re- 60 sides in a coupling member 7, carried by one of the poles 5 and adapted to couple with the other of said poles. The member 7 comprises a sleeve 8, threaded upon the end of one of the poles 5, and the outer end of 65 said sleeve is cut away in its side, as at 9, to receive the end 10 of the associate pole 5. In the sleeve 8 is pivotally mounted a latch 11, the free end of which is adapted to engage in the end 10 of the associate pole, said end being slotted, as at 12, to receive the end of said latch. The opposite end of the latch lies over an opening 14, formed in the sleeve 8, and is provided with a depending cord or chain 15, by which the latch is released from the end 70 75 10 of the pole 5.

By the construction of the coupling member 7 we are enabled to connect the inner ends of the poles 5 and form practically one pole. In some instances we can drape the curtains 80 6 over the member 7, whereby the same will be invisible and the pole will present a neat and attractive appearance.

In Figs. 3 and 4 we have illustrated the poles 5' as having ornamentations 6' instead 85 of coupling members 7, and in Fig. 6 we have shown a screw-bracket 2', having an integral pin 3', upon which a pole can be pivotally mounted. However, our invention partic- 90 ularly resides in the poles and coupling mem- ber illustrated in Figs. 1 and 2 of the drawings.

The poles and their appurtenant parts are constructed of metal, which can be highly polished or finished to conform to the frame with which it is used, and such changes in the 95 size and minor details of construction as are permissible by the appended claims may be resorted to without departing from the spirit and scope of the invention.

What we claim, and desire to secure by 100 Letters Patent, is—

1. In a curtain-pole, the combination with a window-frame, of brackets carried by said frame, poles pivotally mounted upon said brackets and normally lying in longitudinal 105 alinement with one another, a coupling member carried by one of said poles, said member embodying a sleeve recessed at one side, a latch

- pivottally mounted in said sleeve and adapted to engage in the end of the other of said poles, and means to move said latch, substantially as described.
- 5 2. A curtain-pole consisting of brackets, poles pivottally mounted upon said brackets and supporting curtains, a coupling member carried by one of said poles and engaging the other of said poles, and means carried by said 10 member and actuated from the exterior thereof to lock said poles together, substantially as described.
3. A curtain-pole consisting of two pivoted parts, and a coupling member carried by one of said parts and adapted to engage the other of said parts, said member comprising a sleeve and a pivoted latch, substantially as described. 15

In testimony whereof we affix our signatures in the presence of two witnesses.

THOMAS F. THOMPSON.
ALVA PORTER BALDWIN.
